US0D1032863S

(12) **United States Design Patent** (10) Patent No.: **US D1,032,863 S**
(45) Date of Patent: ** Jun. 25, 2024

(54) **FACIAL TREATMENT DEVICE**

- (71) Applicant: **Therabody, Inc.**, Los Angeles, CA (US)
- (72) Inventors: **Jason Wersland**, Los Angeles, CA (US); **Benjamin Nazarian**, Beverly Hills, CA (US); **Jaime Sanchez Solana**, Los Angeles, CA (US); **Eduardo Merino**, Los Angeles, CA (US); **Bill Webb**, San Francisco, CA (US); **Alex Zhu**, Xiamen (CN)
- (73) Assignee: **Therabody, Inc.**, Los Angeles, CA (US)

(**) Term: **15 Years**

(21) Appl. No.: **29/878,978**

(22) Filed: **Jun. 29, 2023**

Related U.S. Application Data

- (60) Continuation of application No. 29/870,357, filed on Jan. 23, 2023, now Pat. No. Des. 994,900, which is a division of application No. 29/772,505, filed on Mar. 2, 2021, now Pat. No. Des. 976,431.

CLAIM

The ornamental design for a facial treatment device, as shown and described.

DESCRIPTION

FIG. 1 is a perspective view of a facial treatment device showing the claimed design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is top plan view thereof; and,

FIG. 7 is a bottom plan view thereof.

The broken lines in the figures show portions of the facial treatment device that form no part of the claimed design.

1 Claim, 6 Drawing Sheets
